[57] CLAIM

The ornamental design for a game cabinet, as shown and described.

DESCRIPTION

FIG. 1 is a perspective view of a game cabinet employing my new design.

FIG. 2 is a top plan view of the game cabinet shown in FIG. 1.

FIG. 3 is a front elevational view of the game cabinet shown in FIG. 1.

FIG. 4 is a right side elevational view of the game cabinet shown in FIG. 1.

FIG. 5 is a rear elevational view of the game cabinet shown in FIG. 1.

The bottom of the game cabinet is a generally planar surface and the left side is a mirror image of the right side.
